UNITED STATES PATENT OFFICE.

SAMUEL R. WILLET, OF PHILADELPHIA, PENNSYLVANIA.

DESIGN FOR A SWAB-CUP.

SPECIFICATION forming part of Design No. 22,086, dated December 27, 1892.

Application filed November 12, 1892. Serial No. 451,824. Term of patent 7 years.

To all whom it may concern:

Be it known that I, SAMUEL R. WILLET, a citizen of the United States, residing at Philadelphia, county of Philadelphia, and State of Pennsylvania, have invented a new and useful Design for Swab-Cups, of which the following is a specification.

My invention is a design for swab cups, and consists in the new and original configuration specifically described in the following specification, and illustrated in the accompanying drawings in which

Figure 1, is a plan view of swab cup embodying my new design, and Fig. 2, is a transverse sectional view of the same taken in the plane indicated by the dotted line $x-x$, Fig. 1.

The main portion of the cup is presented by the inverted shell A, the top a of which is

provided with a relatively large circular opening. Projecting from the side of the cup are laterally extending sections B B, each of which is recessed to form the slot b , base c , and hook finger d , substantially parallel with said base. It will be noted that the slots b are relatively reversed, and that each is open at one end thereof.

Having now described the characteristics of my new design, what I claim is,

The design for a swab cup substantially as herein shown and described.

In testimony whereof I affix my signature in the presence of two witnesses.

SAMUEL R. WILLET.
